UNITED STATES PATENT OFFICE.

HIRAM K. WHITNER, OF CHICAGO, ILLINOIS.

FRICITION FIRE-ESCAPE.

SPECIFICATION forming part of Letters Patent No. 642,889, dated February 6, 1900.

Application filed June 6, 1899. Serial No. 719,632. (No model.)

To all whom it may concern:

Be it known that I, HIRAM K. WHITNER, a citizen of the United States, residing at Chicago, in the county of Cook and State of Illinois, have invented certain new and useful Improvements in Friction Fire-Escapes; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to improvements in friction fire-escapes.

The object of my invention is to not only afford means for descending a rope more securely than heretofore in case of fire cutting off the usual avenues of exit in dwellings and business buildings, but by means such as I hereinafter show I adapt my friction fire-escape to the purposes of additional loads by means of adjustments readily applied. Friction fire-escapes as heretofore constructed required an intelligible action in order that the descent might not be too rapid. Hence when such necessary action was slow in being applied or entirely neglected in a state of great excitement the descent was attended by painful results. In my device, hereinafter set forth, whatever action may be of service will be on opposite lines—that is, relieving the automatically-applied brake force will expedite the descent.

My invention consists in a shoe-brake fire-escape of novel construction having a rope of suitable dimensions rove through a base-piece and a brake-lever, so coacting that a bite upon said rope will be effected by virtue of the weight of said rope and by the weight of the person descending, supplemented by a blocking buffer or pad placed upon said rope.

Figure 1 in the accompanying drawings is a view in perspective of my improved shoe-brake fire-escape as I preferably construct it. Fig. 2 is a vertical section of the same. Fig. 3 is a view in perspective showing a modification of my brake-lever.

When not including the rope in my description hereinafter, I prefer to use the term "traveler" to embrace the combination of

parts embodied in my invention in contradistinction to "device," which embodies rope and all.

55

A represents the fundamental or base piece of the traveler. A' are projections of said base-piece or prolongations ending in enlargements as a means for pivotal connections at A'. a' and a² are piercings of elliptical shape at the extremes of said base-piece A.

B is a bent brake-lever in the form of a right angle, having sections X, X', Y, and Z, forming a circumscribed opening having a rope-bearing free end X' at one extreme 65 and a rope-engaging spur Z at the other extreme. The rounding free end of said brake-lever X' is at home in contact with piercing a', while the other extreme (the end of section Y) is a spur Z, supplemented by 70 thumb-screw B², having a shank b. B' is a pivotal connection for said brake-lever contiguous to said spur Z. The function of said brake-lever is to press upon brake-shoe C, said brake-shoe having an upturn pierced 75 projection C' and stop or trunnion C². Said shoe is rounded at rope-bearing points C³ and C⁴, and in conformity with the shape of the rope the under side of said shoe between said rounded points C³ and C⁴ is hollowed out, 80 grooved, or guttered in order that said rope may travel in line of said under side of said shoe. D is one or more thicknesses of leather or other substance provided with piercings and adapted to bite upon said rope, acting as 85 a buffer, as hereinafter shown.

E is a rope of suitable dimensions rove through the base-piece A and bent brake-lever B and provided with a dead-eye E' at the top and enlargements E² at its bottom in order than when the height is miscalculated the person descending will not drop off the end of said rope. F is a suitable anchorage for said apparatus to be properly fixed to the building.

95

G is a sling to encircle the person about the chest under the arms. G' is a slide to secure said sling about the person descending. G² and H are metal connections between said sling G and piercing C' hereinbefore described.

100

In a reduction to practice I find that the same adjustment does not produce like results upon a rope of same diameter, but of

various textures or twists in the strand. Again, each successive descent upon the same rope reduces the diameter of said rope to a certain extent. Hence I find that in dispensing with the thumb-screw B^2 and forming the side of the spur Z within the brake-lever into a crotch o , Fig. 3, we may obtain a single adjustment bite without the interposition of a shoe; but in a reduction to practice I do not find the results as satisfactory as I had hoped for. Hence I preferably interpose a shoe and provide an adjustable pressure by means of the thumb-screw B^2 and its shank b . In an extensive reduction to practice I find said traveler as herein shown admirably adapted to be used in combination with a wire rope about seven thirty-seconds of an inch in diameter and having a cotton core, about which are laid six twisted strands of seven wire threads each, making a very efficient combination for the purposes to which said device may be applied. However, I do not propose to dedicate to public use the method of dispensing with an interposed shoe and tension thumb-screw.

Starting at the dead-eye E' , following the tracing of the rope rove through the traveler, note its entering piercing a^2 and passing through with a perceptible **S**-bend. Next it lies between the body of the base-piece A and under side of shoe C within section Y of said bent brake-lever and then makes an abrupt bend through piercing a' and brake-lever free end X' . Then of its own weight said rope E makes an abrupt bend, forming another **S**, and is pendent to the bottom of the building. It will be readily understood that the shank b of thumb-screw B^2 rests upon the upper side of the brake-shoe C . Said brake-shoe rests upon the rope E , which in turn rests upon the base-piece A . If we now increase the tension by screwing in said thumb-screw B^2 , by virtue of pivotal point B' the yielding motion of the brake-lever must carry the free end X' from its home in contact with piercing a' , and any weight exerted by the pendent parts E and D must tend to bring said free end X' to its home in contact with piercing a' . This, with the action of the coacting parts, will cause said shoe C to act as a brake to the passing rope E as the traveler descends by virtue of the weight of the person attached to said traveler. We have still another force exerting its influence toward applying the brake. The weight of the person is thrown into said sling G , and, through the connections G^2 , H , C' , C , and C^2 , the last resting upon the horizontal section Y of the bent brake-lever B , in proportion to the amount of weight thrown into sling G will be the amount of pull of stop C^2 upon said horizontal section Y of said brake-lever. While this is not a locking force, because of the relative positions of the various parts contributing to this function, what force we do get will be in proportion to the weight in said sling—a very good feature in an admirable device. With

the parts thus properly adjusted I have made provisions for a recognizable seal, indicating that the adjustment made before placing the device in a position for emergency has not been tampered with. This may be effected by passing a frail thread of wire through the piercings i and i in the thumb-screw B^2 and fastening them to any contiguous part of the device.

The fundamental principle of my invention lies in utilizing the weight of the pendent parts beneath the traveler, so coacting upon a brake-lever that said traveler will be retarded in its passage along a rope, in descending said rope. Hence it must be obvious that if said pendent weight below said traveler causes too great a retardation to said traveler the safest method of affording relief would be to lift said pendent rope, thus allowing the free end of the brake-lever to swing away from its home in contact with extreme a' . Another method of relief would be to take the tension off of the shoe by withdrawing shank b of said thumb-screw B^2 . On the other hand, with sufficient tension upon the shoe-brake a person pulling upon the rope end E^2 or the person descending could add to the retarding force, inasmuch as said pendent rope is within reach while descending. As a precaution in the absence of any intelligible action in connection with the descent of a very heavy person buffer D should be some distance from the ground. When the traveler reaches said buffer D , the latter will contact with the free end X' of said brake-lever, thereby increasing the bite of said traveler upon said rope E .

Having thus fully described my invention, I will now in claims point out what is new and novel.

1. In a friction fire-escape, the combination, with a rope adapted to be placed pendent upon the outside of a building, of a brake-lever having a rope-bearing free end X' , and a spur adapted to engage with said rope, a base-piece adapted to engage pivotally with said brake-lever and provided with piercings adapted to engage with said rope, substantially as and for the purpose set forth.

2. In a friction fire-escape, the combination, with a rope adapted to be placed pendent upon the outside of a building, of a brake-lever having a supplemented spur and a bent long arm provided with a rope-bearing free end X' adapted to engage with said rope, a base-piece adapted to engage pivotally with said brake-lever and provided with piercings adapted to engage with said rope, and a brake-shoe adapted to engage with said supplemented spur, substantially as and for the purpose set forth.

3. In a friction fire-escape, the combination, with a rope adapted to be placed pendent upon the outside of a building, of a brake-lever having a spur provided with a thumb-screw adapted to engage with a brake-shoe and having a long arm provided with a free end X' adapt-

ed to engage with said rope, and a base-piece adapted to engage pivotally with said brake-lever and provided with piercings adapted to engage with said rope, a thumb-screw B^2 , and 5 a brake-shoe C, substantially as and for the purpose set forth.

4. In a friction fire-escape, the combination, with a rope adapted to be placed pendent upon the outside of a building, of a brake-shoe having stop c^2 adapted to engage with a brake-lever and means whereby a person may be suspended from said brake-shoe, a brake-lever adapted to engage with said brake-shoe and provided with a free end X' adapted to engage with said rope, and a base-piece adapted to engage pivotally with said brake-lever and provided with piercings adapted to engage with said rope, substantially as and for the purpose set forth.

20 5. In a friction fire-escape, the combination, with a rope adapted to be placed pendent upon the outside of the building, of a brake-lever B having section Y adapted to engage with brake-shoe C, a base-piece adapted to engage pivotally with said brake-lever and provided

25 with piercings adapted to engage with said rope, and a brake-shoe provided with stop C^2 and means whereby a person may be suspended from said brake-shoe C, substantially as 30 and for the purpose set forth.

35 6. In a friction fire-escape, the combination, with a rope adapted to be placed pendent upon the outside of a building, of a brake-lever B having a spur Z adapted to engage with a thumb-screw B^2 and provided with a free end X' adapted to engage with said rope, and a base-piece adapted to engage pivotally with said brake-lever and provided with piercings adapted to engage with said rope, a thumb-screw B^2 having a shank b and a brake-shoe 40 C, substantially as and for the purpose set forth.

45 7. In a friction fire-escape, the combination, with a rope adapted to be placed pendent upon the outside of a building, of a brake-shoe C having a stop c^2 adapted to engage with brake-lever B and provided with piercing C' adapted to engage with sling G, a base-piece adapted

to engage pivotally with said brake-lever and provided with piercings adapted to engage 50 with said rope, a brake-lever B, and a sling G, and means whereby said sling may be secured to said brake-shoe C, substantially as and for the purpose set forth.

8. In a friction fire-escape, the combination, 55 with a rope adapted to be placed pendent upon the outside of a building, of a base-piece A having projections A' and provided with piercings a' and a^2 adapted to engage with said rope, and a brake-lever adapted to engage pivotally with said base-piece and provided with spur Z, and a brake-shoe C, substantially as and for the purpose set forth.

9. In a friction fire-escape, the combination, 65 of a rope E having a dead-eye E' and enlargement E ^{2} , a buffer D having piercings adapted to engage with said rope, a brake-lever having a free end X' adapted to engage with said buffer, and a base-piece adapted to engage pivotally with said brake-lever and provided 70 with piercings adapted to engage with said rope, substantially as and for the purpose set forth.

10. In a friction fire-escape, the combination, 75 a rope E having dead-eye E' and enlargement E ^{2} , a buffer D having piercings adapted to engage with said rope, a brake-lever having a free end X' adapted to engage with said buffer and provided with spur Z, a thumb-screw B^2 adapted to engage with said spur Z, and 80 with brake-shoe C, a base-piece A having projections A' adapted to engage pivotally with said brake-lever and provided with piercings a' and a^2 adapted to engage with said rope, and a brake-shoe C having stop c^2 adapted to 85 engage with the horizontal section Y of said brake-lever and provided with piercing C', a sling G, adapted to engage with said piercing C', substantially as and for the purpose set forth. 90

In testimony whereof I affix my signature in presence of two witnesses.
